UNITED STATES PATENT OFFICE.

FREDERICK GARDNER, OF CHICAGO, ILLINOIS.

APPARATUS FOR DISINFECTING WATER-CLOSETS AND THE SEATS THEREOF.

SPECIFICATION forming part of Letters Patent No. 716,335, dated December 16, 1902.

Application filed July 3, 1901. Serial No. 66,993. (No model.)

To all whom it may concern:

Be it known that I, FREDERICK GARDNER, of Chicago, in the county of Cook, and in the State of Illinois, have invented certain new and useful Improvements in Apparatus for Disinfecting Water-Closets and the Seats Thereof; and I do hereby declare that the following is a full, clear, and exact description thereof, reference being had to the accompanying drawings, in which—

Figure 1 is a perspective view of a water-closet provided with a movable cover embodying my invention for rendering the seat antiseptic. Fig. 2 is a longitudinal sectional view of the cover illustrated in Fig. 1, and Fig. 3 is a perspective view of a water-closet provided with a stationary back embodying my invention for rendering the seat antiseptic.

The object of my invention has been to provide means for rendering a water-closet sanitary and the closet-seat antiseptic, so that danger to a person using the seat of contamination by disease from a person who previously used the same is prevented; and to such ends my invention consists in the device for rendering water-closets and the seats thereof antiseptic, substantially as hereinafter specified.

In carrying my invention into practice I provide, as illustrated in Figs. 1 and 2, a seat A, which is connected to a base B by hinges C and D. The base is secured to the water-closet bowl E, as by screws passing through openings in such bowl and into the under side of the base. A cover F is hinged to the base in such position that it can be swung down over the seat. On the under side of the cover a sheet-metal box G is secured, as by having the bottom g of such box screwed to the under side of the cover. Low sides are preferably secured to the bottom of the box, and the top g' of the box is hinged to one of such sides. The free end of the cover is provided with a spring-clip g², that is adapted to catch on a bead formed on the adjacent side of the box. The cover of the box is perforated or is formed or provided with wire-netting. A felt or other absorbent sheet or pad H is contained within the box, and such pad is impregnated with any suitable antiseptic material. The box-cover g' is preferably provided with strips or wires g³ on its under surface, and the outer strips are pref-

erably connected together to form a closed figure.

In the use of my device the box-cover g' is swung open, the pad H, properly charged with the antiseptic material, is placed within the box, and the box-cover g' is latched in place by the engagement of the clip with the bead. When it is desired to disinfect the water-closet seat, the cover F is turned down upon the closet-seat and the disinfecting gases or vapors pass from the pad through the perforations in the box-cover and reach the water-closet seat, which they disinfect. The cover can then be raised and the seat safely used. When the cover is turned down upon the seat, the gases or vapors will pass into the interior of the bowl and disinfect the interior thereof. If desired, the seat can be turned back against the cover and the seat and disinfecting substance thus be brought together. The strips g³ and g³ keep the clothing of a person using the closet from coming into contact with the surface of the box-cover g'. As the outer strips form a closed figure, they serve to prevent the lateral escape of the vapors or gases between the seat and cover.

The strips g³ and g³ can, if desired, be omitted.

In the embodiment of my invention illustrated in Fig. 3 a back I is secured in a substantially vertical position, as to a wall, and a box K, preferably constructed like the box G, before described, is secured thereto. A seat L is hinged to the back, preferably by spring-hinges M and M. The springs of the hinges throw the seat against the back when the former is not in use, and thereby cause the seat to be automatically disinfected.

It is obvious that changes which are within the scope of my invention can be made in the above-illustrated constructions. For instance, the top can be hinged at its upper edge when in the vertical position and can be made to swing down against the bottom of the seat when the seat is in the vertical position, so that the lower surfaces of the seat will be disinfected.

Having thus described my invention, what I claim is—

1. An apparatus for disinfecting water-closets and the seats thereof, consisting of the combination of a seat and a sheet-metal box

that is fastened or attached to the seat, such box containing an antiseptic-impregnated pad, and the cover thereof being perforated, substantially as and for the purpose described.

2. An apparatus for disinfecting water-closets and the seats thereof, consisting of the combination of a seat, a sheet-metal box that is hinged to the seat, such box containing an antiseptic-impregnated pad, the cover of the box being perforated, and ribs or strips on such cover, substantially as and for the purpose described.

3. An apparatus for disinfecting water-closets and the seats thereof, consisting of the combination of a seat, a sheet-metal box that is hinged to the seat, the cover of such box being perforated, ribs on the box that form

a closed figure, and an antiseptic-impregnated pad contained in the box, substantially as and for the purpose described.

4. An apparatus for disinfecting water-closets and the seats thereof, consisting of the combination of a seat, a sheet-metal box whose bottom is hinged to the seat, the top of the box being hinged to the bottom thereof and being perforated, and an antiseptic-impregnated pad contained in the box, substantially as and for the purpose described.

In testimony that I claim the foregoing I have hereunto set my hand this 29th day of May, 1901.

FREDERICK GARDNER.
